(57) **CLAIM**

The ornamental design for a necklace pendant, as shown and described.

DESCRIPTION

FIG. 1 is a front top right perspective view of a necklace pendant in an open configuration;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof;

FIG. 8 is a rear top right perspective view thereof;

FIG. 9 is a front top right perspective view of a necklace pendant in a closed configuration;

FIG. 10 is a front view thereof;

FIG. 11 is a rear view thereof;

FIG. 12 is a first side view thereof;

FIG. 13 is a second side view thereof;

FIG. 14 is a top view thereof;

FIG. 15 is a bottom view thereof; and,

FIG. 16 is a rear top right perspective view thereof.

The broken lines shown in the drawings represent portions of the necklace pendant which form no part of the claimed design.

1 Claim, 10 Drawing Sheets
